UNITED STATES PATENT OFFICE.

JOHN GEORGE GIESBERG AND EDWARD SCHEULTZ, JR., OF HOUSTON, TEXAS.

BOX-FASTENER.

SPECIFICATION forming part of Letters Patent No. 479,416, dated July 26, 1892.

Application filed April 15, 1891. Serial No. 389,032. (No model.)

To all whom it may concern.

Be it known that we, JOHN GEORGE GIESBERG and EDWARD SCHEULTZ, Jr., citizens of the United States, residing at Houston, in the 5 county of Harris and State of Texas, have invented a new and useful Cover-Fastener, of which the following is a specification.

This invention is an improvement in cover-fasteners; and it has for its objects to produce 10 a cover-fastener which will securely fasten the cover to a box, which will be simple, cheap, and effective.

With these objects in view the invention resides in the various novel details of construction and in the combination of parts hereinafter fully described, and particularly pointed out in the claim.

In the drawings in which we have illustrated our invention, and in which like letters 20 of reference indicate corresponding parts, Figure 1 is a perspective view of one end of a box provided with our device. Fig. 2 is a similar view of a box provided with another form of our device, and Fig. 3 is a view showing in 25 detail the parts of the fastener of Fig. 1 removed from the box. Fig. 4 is a sectional view of the form shown in Fig. 2, and Fig. 5 is a sectional view of the form shown in Fig. 1.

In the drawings, the letter A designates a 30 box, a receptacle, or the like, and B designates the cover therefor. The box A is provided with strips a at either end, and the cover B is provided with depending strips b at either end which are adapted to fit down over the 35 ends of the box upon the strips a. The cover B has extending downward from the strips b bolts b', which have their bodies cut away near the ends to form necks b². (See Figs. 4 and 5.) The strips a are provided with openings 40 a', through which the bolts b' may pass, and on their under sides the strips a are provided with plates c, which form part of and are the bases upon which the fasteners C are built and secured to the strips a. As shown in Fig. 45 1, the fastener C consists of the plates c, secured to the strip, as described, a slotted plate c', pivoted to said plate and having an extension c², controlled by a guide-loop c³, which limits the movement of the said slotted plate

50 c'. The plate c' is provided with an upturned piece c⁴, to serve as a thumb-piece. The plate c is perforated in order to permit the passage through it of the bolt b', and the plate c' is also perforated at c⁵ for a similar purpose and

is provided with a slot c⁶, which connects with 55 said opening. When the bolt has passed through the perforation c⁵, it may be secured from being retracted by turning the plate c' so that the neck b² will be caught in the slot c⁶.

As shown in Fig. 2, the fastener consists of 60 a plate c, perforated to permit of the passage of a bolt b' and a plate c⁷, secured thereto by means of the loops c⁸, embracing the narrowed portions in such position that the plate may be reciprocated. This plate c⁷ is provided 65 with a perforation c⁹, from which extends a slot c¹⁰. The operation of this form of the device is similar to that just described and is easily perceived from an inspection of the drawings.

With both forms of our device we use a locking-pin D. This pin D rests in an opening d, made in the strip a, and may be either spring-pressed or not, as is deemed most desirable, the pin being provided with a stop d' to 70 limit its downward movement and keep it in place. When not provided with a spring to press it downward, the pin is allowed to drop by gravity.

The operation of the pin in locking the device is simply by dropping in front of the upturned piece c⁴ whenever the neck b² has been caught in the slot c⁶.

We may use our cover-fastener for a variety of purposes; but we prefer to use it as a box- 85 fastener.

Having thus described our invention, what we claim, and desire to secure by Letters Patent, is—

In a cover-fastener, the combination of the 90 base-plate provided with a perforation adapted for the reception of a bolt, a movable plate mounted on the base-plate and having a perforation and a slot connected with the same and having its movement limited by guides 95 and provided with an outwardly-turned lug c⁴, a bolt provided with a neck, and a gravity locking-pin arranged in an opening of the base-plate and adapted to engage the lug c⁴, substantially as described.

In testimony that we claim the foregoing as our own we have hereto affixed our signatures in presence of two witnesses.

JOHN GEORGE GIESBERG.
EDWARD SCHEULTZ, JR.
